UNITED STATES PATENT OFFICE.

EDWARD R. HIBBARD, OF OAK PARK, ILLINOIS, ASSIGNOR TO GRIP NUT COMPANY, OF CHICAGO, ILLINOIS, A CORPORATION OF ILLINOIS.

NUT-LOCK.

1,261,232.

Specification of Letters Patent.

Patented Apr. 2, 1918.

Original application filed October 25, 1912, Serial No. 727,748. Divided and this application filed April 17, 1915. Serial No. 21,989.

To all whom it may concern:

Be it known that I, EDWARD R. HIBBARD, a citizen of the United States, residing at Oak Park, in the county of Cook and State 5 of Illinois, have invented certain new and useful Improvements in Nut-Locks, of which the following is a description.

This application is a division of an application heretofore made by me, which was 10 duly filed on October 25, 1912, Serial No. 727,748.

This invention belongs to the general class of devices intended to so engage with a bolt as to prevent the accidental disengagement 15 of the nut therefrom, and has for its object the economical and extremely efficient device for the purpose stated. To this end my invention consists in the novel construction, arrangement and combination of parts 20 herein shown and described, and more particularly pointed out in the claims.

In the drawings, wherein like reference characters indicate like or corresponding parts,

25 Figure 1 is a bottom plan view of my improved nut lock;

Fig. 2 is a transverse section of the same on the line 2, 2, taken in the direction indicated by the arrows; and

30 Fig. 3 is a similar section taken on the same line, but in the opposite direction from that indicated in Fig. 2.

My improved nut lock is constructed from 35 a single sheet of metal, and preferably stamped out into the form indicated. For convenience I have called this "cup-shaped" in the specification, and in some of the claims, owing to the fact that all the marginal edges are bent downward as indicated.

40 In the drawings, 1 indicates a suitable sheet of metal, having punched in it a bolt hole 2. The wall of the bolt hole is severed as at 3, and laterally offset as at 4, 5, shown in Fig. 3. The wall of the bolt hole is preferably stamped out substantially V-shaped, as shown, so as to properly engage with the depression between two threads on the bolt to which it may be applied, and the lateral offset is sufficient, not only to permit the 50 lock to properly thread upon the bolt, but

also preferably offset to an extent slightly greater or less than the distance between two threads on the bolt, so as to firmly frictionally engage on the thread. The marginal edges of the nut, as at 6, are bent or flanged 55 in the form indicated, and at substantially right angles to the face of the lock, the flanged portions 6 being preferably substantially integral, as indicated. This construction not only permits a convenient means to 60 engage the wrench with the nut lock, but serves a still more important purpose when the lock is used with the recessed face for the working face. When so used the outer edges of the flanges 6 will first contact with 65 the holding nut, or equivalent object, and further setting the lock with the wrench will cause the working face thereof to spring downward, the plate being sufficiently resilient to permit this slight action in the 70 preferred construction. This spring action serves to more firmly and securely retain the nut lock in position, and in practical use has been found very efficient for the purpose stated.

75 Obviously, the form of the nut lock is not material, and it may be either square, or polygonal as indicated in the drawings.

It will be noted that where in the claims I have referred to a "cup-shaped" disk, I 80 wish to be understood as meaning a disk constructed in the manner shown in the drawings, with the depending edges 6. The same will be understood where the term "flanged" may be used.

Having described my invention, what I claim as new and desire to secure by Letters Patent is:—

1. A nut lock, comprising a disk having a bolt hole formed therein, the wall of which is V-shaped to form a single thread adapted to engage a bolt thread, and severed and permanently offset to permit the same to engage with a bolt thread, the disk being flanged around the edge thereof substantially as described.

2. In combination with a bolt a nut lock, comprising a disk having a bolt hole formed therein the wall of which is V-shaped to form a single thread, adapted to engage a

bolt thread, and severed and permanently displaced on opposite sides of the disk, a distance varying from the distance between the threads of the bolt, said disk being flanged on all of the edges thereof substantially as described.

In testimony whereof, I have hereunto

signed my name in the presence of two subscribing witnesses.

EDWARD R. HIBBARD.
